BY J. Edward Maybee
ATTN:

UNITED STATES PATENT OFFICE.

WILLIAM BANIKA, OF STAMFORD, ONTARIO, CANADA.

CIRCUIT CLOSER.

Application filed September 18, 1925. Serial No. 57,182.

This invention relates to circuit closers for indicators for indicating the intended changes of direction of a vehicle, especially an automobile, and my object is to provide a device of this character which may be cheaply manufactured, yet durable and efficient and which may be readily connected with the steering apparatus of an automobile.

10 I attain my object by means of the constructions hereinafter described and illustrated in the accompanying drawings in which—

Fig. 1 is a side elevation of part of the frame and steering mechanism of an automobile showing my device in position thereon;

Fig. 2 a front elevation of the same;

Fig. 3 a wiring diagram of my indicator;

20 Fig. 4 a cross section of my switch box;

Fig. 5 a section on the line 5—5 of Fig. 4;

and

Fig. 6 a section on the line 6—6 of Fig. 4.

In the drawings like numerals of reference 25 indicate corresponding parts in the different figures.

1 is the casing of a switch box in which a spindle 2 is journaled. On the spindle is secured a U shaped arm 3 having its legs 3^a provided with connectors 4 suitably insulated from the arm and being in the form of rollers rotatable on the legs 3^a. These connectors are adapted to form an electrical connection between one of the two contacts 35 5, 6 and a third contact 7 which is common to the first two contacts.

Referring to Figs. 4, 5 and 6, it will be noted that all the contacts are arcuate in shape and the contacts 5 and 6 are located at 40 opposite sides of the switch box and are connected with the terminals 5^a and 6^a respectively. The contact 7 is connected to the terminal 7^a and extends round the switch beside the other contacts but is insulated in 45 any suitable manner from them. This is preferably accomplished by providing a block 8 of insulating material having arcuate slots 9 therein adapted to receive the connectors 4. The walls of the slots are 50 grooved out to receive the arcuate contacts which are of substantially the same radius so that by revolving the spindle 2, and thus the arm 3, in either direction, a connector 4 will be engaged with one of the contacts 5 or 6 and the contact 7. A spring 10 connected with the spindle 2 and the casing 1

tends to normally maintain the connectors 4 out of engagement with all the contacts.

On the outer end of the spindle is secured a lever 11 which is connected with a suitable part of the steering mechanism of an automobile. Preferably the opposite ends of the lever are connected by means of the flexible connections 12 with the steering post 13. The switch box is removably carried on a bracket secured to the frame member 14 adjacent the steering mechanism. The bottom 15 of the switch box is secured to the bracket and has its ends bent over and inwardly directed to form a socket adapted to slidably receive the laterally directed ends 1^a formed on the sides of the container 1.

The indicating device includes a casing 16 which is partitioned off to form three compartments in which the electric bulbs 5^b, 17 and 6^b are suitably carried. The casing is provided with glazed rear and front sides and the portions of each glass behind and in front of the different compartments will be marked to indicate "Left", "Straight ahead" and "Right". This may be done by coloring these portions to contrast with the portions in front and behind the adjacent compartment. The bulbs 5^b and 6^b are connected by wires 5^c and 6^c with the terminals 5^a and 6^a respectively and the terminal 7^a is connected by a wire 7^b with a battery 18. All the bulbs and the battery are grounded on the frame of the vehicle and the wire 7^b has a manually operated switch 7^c connected intermediate its ends so that the bulbs may be cut out when desired.

The driver may indicate to a traffic officer, whether he desires to turn to the right or left or go straight ahead, by means of manually operated switches 6^d, 5^d and 17^a suitably connected to the battery and to the bulbs 6^b, 5^b and 17. The manually operated switches are carried on the steering wheel, 100 the switch 17^a being connected, by wire 17^b, to bulb 17. The switches 5^d and 6^d are connected by wires 5^e and 6^e with wires 5^c and 6^c.

The mode of operation, assuming the driver has turned the steering wheel to 105 make a right hand turn and the switch 7^c is closed, is as follows: The steering post is partially rotated to rock the lever 11 and thus the spindle 2 and arm 3 which moves the connector 4 adjacent the contact 6 into engagement therewith and also with the contact 7. The current then flows from the battery

to the bulb 6^b and when the steering wheel is turned to normal position again after the corner is turned, the bulb is cut out. If it is necessary to stop the vehicle for any length of time with the front wheels turned, the switch 6^d or 5^d is opened to cut out its bulb which otherwise would remain lit and thus run down the battery. By operating any one of the switches 5^d, 6^d or 17^a the driver will give an indication which way he desires to go before the wheels have been turned.

What I claim is:

1. A switch including a casing having a block of insulation therein; a rotatably mounted spindle, the insulation being slotted concentric with the spindle; three arcuate contacts mounted in the insulation adjacent the slotted portion, two of the contacts being positioned at opposite sides of the slotted portion and the third contact being common to the other two; a U-shaped arm carried by the spindle; and rotatable connectors carried by the legs of said arms and adapted to be received in the slotted portion, each of the connectors being adapted to engage the said

third contact and one of the other two contacts; and a spring connected with the spindle and the casing to normally hold the connectors out of engagement with all the contacts.

2. The combination with a vehicle provided with steering mechanism, of a switch mounted on a stationary part of the vehicle and including three arcuate contacts of substantially the same radius and insulated from one another, two of the contacts being positioned at opposite sides of the switch and the third contact being common to the other two; a spindle journaled concentric with the contacts; a U-shaped arm carried by the spindle adapted to engage the said third contact and either one of the other two contacts; and a lever secured to the spindle; and flexible connections connected with opposite ends of the lever and with a movable part of the steering mechanism.

Signed at Toronto, this 1st day of Sept., 1925.

WILLIAM BANIKA.
